UNITED STATES PATENT OFFICE

EARL D. TUBBS, OF NEW YORK, N. Y.

DEVICE FOR APPLYING AND TWISTING WIRE

Application filed April 28, 1928. Serial No. 273,571.

This invention relates to devices for applying wire to boxes, bundles, bales or the like, and the improvements are directed to novel and improved means for twisting the 5 free ends of said wire.

The invention contemplates the provision of a device of the above-mentioned character which is exceedingly compact in arrangement and which requires a minimum of effort to operate the same.

The invention includes a mechanism of co-operating parts adapted to first tighten the wire encircling or encompassing the box, or the like; second, to twist the overlapping 15 portions thereof and finally to clip off the free ends adjacent the twisted wire.

Another object is to provide twisting means including a rotatable member having a radial slot extending transversely thereof, 20 the outer portion of said slot presenting flaring sides to facilitate the entrance and removal, before and after twisting, respectively.

Still another object of the invention is to 25 provide removable stationary means for positioning said rotatable member within a carrier member, said means extending co-axially of said rotatable member, from both sides thereof, and presenting end slots substantially conforming to the slot in said member.

Still another object is the provision of removable stationary means, composed of two parts having a slot therethrough and extending longitudinally to the center of the 35 closed ends thereof, and a chamber of a sufficient diameter within said parts, between the closed ends and the sides of the rotative member to permit the free rotation of the wire during the twisting operation.

40 A further object is to provide a rotatable member, slotted in the manner set forth, said member presenting oppositely disposed recesses arranged centrally thereof and coinciding with the inner end of the slot to prevent nicking of the wire during the twisting 45 operation, and subsequent shearing thereof.

A still further object is to provide a clutch mechanism whereby the tightening and twisting operations may be performed independently of one another.

A still further object is to provide a periodically operable mechanism whereby the free ends of the wire may be severed after the twisting operation.

A still further object resides in the provision of cutting or severing means, adjustably mounted and positioned to selectively operate on the free ends of the twisted wire.

With these objects in view, together with others which will appear as the description 60 proceeds, the invention resides in the novel formation, combination and arrangement of parts, all as will be described more fully hereinafter, illustrated in the drawings, and particularly pointed out in the claims.

In said drawings:

Figure 1 is a sectional view of the housing or closure for said device, the mechanism of said device being shown in front elevation and preparatory to the performance of 70 the tightening operation.

Fig. 2 is a view like unto Figure 1, but showing the mechanism in rear elevation.

Fig. 3 is a sectional view taken substantially on the line 3—3 of Fig. 1 and illustrating the mechanism in end elevation.

Fig. 4 is a vertical transverse section taken substantially on the line 4—4 of Fig. 1, with parts broken away.

Fig. 5 is an end elevation of the mechanism, as viewed from the right of Fig. 1, a portion of the housing being removed.

Fig. 6 is a view somewhat similar to Fig. 5, but illustrating the operation of certain oscillatory means carrying one of the cutters.

Fig. 7 is a vertical sectional view, somewhat enlarged, and taken on the line 7—7 of Fig. 1, and illustrating the stationary means for positioning a rotatable element within a carrier member.

Fig. 8 is a sectional view, taken on the line 8—8 of Fig. 7, said stationary means being shown in elevation.

Fig. 9 is a central sectional view of the rotatable member illustrating the recesses, 95 oppositely disposed, and arranged centrally to coincide with the inner portion of a radial slot in said member.

Fig. 10 is a side elevation of said rotatable member, illustrating the flaring slot and an 100

annular groove, surrounding both of said recesses, and adapted to receive the inner ends of said stationary means.

Fig. 11 is a sectional view of said rotatable member and associated stationary means, detached from the carrier member, and diagrammatically illustrating the twisted wire.

Fig. 12 is an end elevation of one of the stationary members, to depict the slot arranged in the outer end thereof.

Before presenting the invention in its detailed form, it is pointed out that the device contemplates manually-operated means, in the form of a crank, or the like, adapted to travel in an orbit, its rotation in one direction, or phase of the orbit, operating the tensioning or tightening of a wire previously wrapped around a box, or the like, the twisting operation and the severing operation being inoperative during this tightening of the wire. As will presently appear a clutch mechanism is provided which is adapted to free certain rotative parts and to permit the rotation of the crank in an opposite phase of the orbit, for operating the twisting mechanism and the periodically operated mechanism for severing the undesired ends of the twisted wire.

Thus, briefly, I propose to provide means for tightening the wire previously wrapped around a box, or the like, and through certain selectively operated mechanism to twist the overlapping portions and finally to sever the undesired wire ends at the outer termination of each, each of the operations being sequentially timed and adapted to reduce the aforesaid operations to a minimum.

In carrying out the aforesaid objects, I provide a manually-operated crank 15, suitably affixed to one end of a shaft, suitably journaled in the side member 17 of a closure 18, said shaft 16 extending longitudinally of said closure and having its other end journaled in a bracket 19 rising from the base 20 of said closure. Disks 21 and 22, having a depending portion 23 and 24 respectively, are fixedly secured to said shaft by means of pins 25 and 26 (see Fig. 1), while ratchet wheels 27 and 28 are loosely journaled thereon, the former being pinned to a pinion 29, loose on said shaft, while the latter is pinned to a bevel gear 30 also loose on said shaft 16, each of said depending portions 23—24 pivotally carrying spring-pressed pawls 31—32, oppositely disposed with respect to said ratchet wheels 27 and 28.

Meshing with said bevel gear 30 is another bevel gear 33 carried by the upper end of a vertical shaft 34, journaled in arm 19^a of said bracket 19, the lower end of said shaft being journaled in a plate 35 carried by the base 20, and adjacently carrying a worm 36 meshing with worm 37 splined to horizontal stub shaft 38 rotatively mounted in bracket 39, as clearly shown in Fig. 3.

Considering now the first orbital travel of the handle 15, with reference to Fig. 5, it will be observed that the rotation of the same to the right will revolve said shaft 16 and the disks 21—22 pinned to said shaft. However, in this rotation it is only desired to convey motion to said bevel gear 30 and hence the arrangement of said pawl 32, as indicated in Fig. 4, with respect to said ratchet wheel 28, causes the rotation of the latter and its pinned bevel gear 30, said pawl 31, in the meantime riding over the teeth of said ratchet wheel 27. The rotative motion of said bevel gear 30 is conveyed to the worms 36—37 through the mechanism aforesaid and thus the motion is transmitted to said horizontal shaft 38. In this particular instance there is no restriction to the operation of said handle to the right as shown in Fig. 5, it being understood that said ratchet wheel 27 and the pinion 29 remains stationary during this operation.

As clearly shown in Fig. 3, said shaft 38 is provided with a head 39^a, carrying forwardly directed pins 40 and 41, for a purpose to be presently disclosed in detail.

Driven gear 42, enmeshed with gear or pinion 29 is carried by shaft 43, rotatively mounted in standards 44 and 45 rising from base 20 and integrally cast therewith if desirable, the outer ends of said shaft 43 fixedly carrying hubs 46 and 47 having diametrically opposed projections 48—49 and 50—51 respectively.

The carrier member 52 is suitably secured to said base member 20, as by screws 53 and 54, (see Fig. 7) and is provided with a medial recess 55 to receive the toothed rotatable member 56, said carrier member being provided with longitudinally extended aligned bores 57 and 58 for the reception of the removable stationary means 59 and 60. Upon inspection of Fig. 1, it will be noted that said rotatable member 56 meshes with said gear 42, and hence the said member 56 is free to rotate in the aforesaid recess 55, but upon inspection of Fig. 8, it will be observed that said means 59 and 60 is held stationary within said bores 57 and 58 in view of set screws 61 and 62, and their removal is effected by the release of said set screws.

The specific construction of said rotatable member 56 is clearly shown in Figs. 9 and 10, wherein it will be observed that a radial slot 63 is provided, the same extending transversely thereof from the axis of said member to the periphery thereof, that portion adjacent the axis presenting substantially parallel sides 64 from which said slot diverges or flares outwardly, as indicated at 65 toward the periphery of said member. As clearly shown in Fig. 9 the opposite sides of said member is flared as indicated at 66 and 67, the same being in the nature of recesses and co-axially blending with the inner end of said slot 63.

Arranged concentric with said recesses 66 and 67 are annular grooves 68 and 69, which receive the inner ends of stationary means 59 and 60 respectively, as shown in Fig. 8, said stationary means comprising a pair of tubular elements, each having their closed outer ends 70 and 71 provided with slots 72 and 73 substantially conforming to recess 63 of said member 56.

Extending laterally from said standard 44 is an arm 74, pivotally supporting a rock lever 75, as indicated at 76, (see Figs. 2 and 4), the upper end of said lever extending through slot 77 in the cover 78 of said closure 18, while the lower end of said lever 75 is pivotally connected to a horizontal rod 79, as shown at 80, the inner end of said rod being normally positioned in an aperture 81 in said gear 42. Said lever 75 and its associated parts comprise literally a clutch mechanism, since the entrance of the end of said rod 79 within aperture 81 normally restrains the rotation of said gear 42. In the preferred embodiment of the invention, as illustrated in the drawings, I have provided two apertures in said gear 42, one numeraled 81 aforesaid, the other, 82, (see Fig. 4) being diametrically opposite 81 and adapted to receive the end of said rod 79 at certain intervals as will be pointed out hereinafter. Obviously, three or more apertures may be provided depending upon the phase of rotation of said gear 42.

The cutting mechanism previously referred to, comprises a pair of cutters 83 and 84, 35 adjustably carried by the oscillatory members 85 and 86, respectively, each being pivoted to opposite sides of said carrier member 52, as indicated at 87 and 88, and maintained in a position with the cutters elevated by means of springs 89 and 90, the former extending and joined to arm 74, while the latter is joined to arm 91 extending laterally from standard 45. While in this position the rear portion of the upstanding arms 45 85^a and 86^a each abut the hubs 46 and 47, (see Figs. 4 and 5), said arms being recessed as indicated at 92 and 93, for the reception of rotatable elements 94 and 95 in the paths of the projections carried by said hubs 46 and 50 47.

Positioned adjacent the cutter 84, (see Figs. 1 and 5), is a clamping lever 96, eccentrically pivoted to a bracket 98, as indicated at 97, said bracket being slotted as indicated 55 at 99, and in line with the axis of said rotatable member 56.

The device is exceedingly compact and may be carried by means of handle 100 positioned on the cover 78, and hence when the said device is to be used it is transported and placed upon the top of a box, or the like, to be wire-bound, whereupon the end of a suitable length of wire is placed in slot 99 and the lever 96 drawn down to the position 65 shown in Fig. 6 thus firmly clamping said

end. The wire is next inserted through the side opening 52^a of carrier member 52, thus passing through slots 73, 63 and 72, (see Fig. 8) and to the rear thereof; said wire then being wrapped around the box, or the like, 70 brought upwardly, again inserted, or literally pushed into the slots aforesaid, its free end being placed between pins 41, wrapped around pin 40 and thence between pins 41 to securely bind said end, as shown in dotted 75 lines in Fig. 1. In its present condition the wire is, of course, loosely wrapped around the box, or the like, and the first operation is to draw the same taut. Said crank 15 is now rotated to the right, as viewed in Fig. 5, 80 whereupon the cooperating pawl and ratchet 32—28 couples said bevel gear 30 to shaft 16 and communicates rotative movement to said head 39, on shaft 38, through the intermediary of the gearing 36—37 and 33, and 85 in view of the positioning of the pins 40—41 on said head 39 the free end of the wire proceeds to wrap thereon until the complete length of said wire is sufficiently tightened about the box. This completes the tightening 90 operation.

The next operation, to wit: twisting, is accomplished by conveying rotative motion to said member 56 in whose slot 63 the wire is positioned in a two-strand relation. As a 95 first step said rock lever 75 is oscillated to retract the end of rod 79 from apertures 81 in said gear 42, whereupon the crank 15 may be rotated to the left, as viewed in Fig. 5, 100 said ratchet wheel 27 and pawl 31 co-operating to lock pinion 29 to said shaft 16 and its rotative motion is transmitted to said member 56 by means of gear 42. It will, of course, be understood that in this operation the pawl 32 rides over the teeth of ratchet wheel 28 105 and hence the essential elements of the tightening mechanism are inactive. Further, the retraction of said rod 79 stretches its encircling spring 79^a, having one end secured to standard 44 and the other to the pivotal connection 80, and as said gear 42 rotates the ends of said rod 79 intimately contacts, or slides over the face of said gear 42 and in a position to slip into aperture 82 when said gear has made a half revolution, thus locking 110 the parts constituting the twisting mechanism.

Considering now the position of the wire passed through said slots 73—63—72, in double or two-strand formation, it will be understood that normally the two wires lie side by side in the same horizontal plane, this condition is made possible by selecting a member 56 and tubular members 59 and 60 having the inner portion of their slots substantially conforming to the diameter of the wire being used. With this in mind it is obvious that the side by side arrangement of the wires in slots 72 and 73 remains constant during the 120 twisting operation and that the torque applied 125 to the wire is transmitted to the wire 130

to the wire is due to the rotation of said member 56, and between said slots 72 and 73, in which slots the ends of the wire are clinched.

The number of twists to which the wires are subjected may be varied as desired. For instance, the apertures 81 and 82 permit a half-revolution of said gear 42, but manifestly one of the apertures may be rendered inoperative, as by plugging, for instance, to allow said gear 42 to make one complete revolution and an attendant increase in the revolutions of said rotative member 56 before the clutch mechanism operates, and thus the number of twists in the wires is increased.

After the wires have been twisted, as desired, it becomes necessary to cut off the undesired ends thereof beyond the twisted portion. In the present instance the undesired ends are, first, that end previously clamped beneath said lever 96 and, second, that end wrapped around said pins 40—41, said cutting of the ends being of course simultaneous. For this purpose cutters 83 and 84 are provided and carried by oscillatory members 85 and 86 pivotally supported to the carrier member as pointed out hereinbefore, and adapted to oscillate to bring said cutters into contact with the proper ends of the wires to be severed. The operation will be understood upon inspection of Fig. 6, wherein it will be noted that the rotation of gear 42, during the twisting operation, likewise revolves the hubs 46 and 47, on its shaft 43, and brings a selected projection into contact with a rotatable element of said oscillatory members for the purpose specified. In Fig. 6 the projection 51 has been rotated from the position shown in Fig. 5 and is cooperating with rotatable element 95, in recess 93, to depress

the cutter against the end of the wire. A similar operation attends both oscillatory members and the cutters associated therewith. The cutters 83 and 84 are adjustably mounted in oscillatory members 85 and 86 by means of set-screws 101 and 102, as clearly shown in Fig. 4, and since only a single wire of the double strand formation is to be severed by said cutters, the cutter 83 is positioned out of the vertical axis of slot 72, while its companion 84 is positioned within the vertical axis of said slot 73.

In view of the flaring of the sides 65 of said slot 63, of member 56, the ordinary tendency of the wire to bind in said slot 63, is obviated, and further its quick removal is facilitated. The flared recesses 66 and 67 of said member 56 prevents notching or nicking of the wires when being twisted and removes the liability of a break at this point. This is a feature of some importance.

As previously suggested, the essential elements of the twisting mechanism are readily removed and may be substituted for parts having larger or smaller recesses to accommodate the particular size of wire to be used.

Having thus fully described this invention, I hereby reserve the benefit of all changes in form, arrangement, order, or use of parts, as it is evident that many minor changes may be made therein without departing from the spirit of the invention or the scope of the following claims.

I claim:

1. In a device of the character described, a rotative member having a radial slot for the reception of wires to be twisted, means for imparting rotation to said member and stationary members rotatably supporting said member and having slotted portions conforming to said slot in said member and adapted to clinch the ends of the wires during the twisting operation.

2. In a device of the character described, a rotative member having a radial slot for the reception of wires to be twisted, means for imparting rotation to said member and stationary members rotatably supporting said member, said members extending from the opposite sides of said member and each having a slotted portion conforming to said slot in said member and adapted to clinch the ends of the wire during the twisting operation.

3. In a device of the character described, a rotative member having a radial slot presenting diverging side walls for the reception of wires to be twisted, means for imparting rotation to said member, and stationary members adapted to support said member and extending axially thereof, said members having their outer ends slotted to conform to the slot in said rotative member and adapted to clinch the ends of the wire during the twisting operation.

4. In a device of the character described, a rotative member having a transverse radial slot presenting diverging side walls, for the reception of wires to be twisted, means for imparting rotation to said member, a carrier member having a recess for the reception of said member and further having longitudinal bores opening from the face of said member, and stationary members adapted to support said rotative member in said carrier member, said stationary members extending axially of said rotative member and having their outer ends slotted to conform to the slot in said rotative member and adapted to clinch the ends of the wire during the twisting operation.

5. In a device of the character described, a rotative member having a transverse radial slot presenting diverging side walls for the reception of wires to be twisted and having conoidal recesses on both faces concentric with said slot, means for imparting rotation to said member, a carrier member having a recess for the reception of said member and further having longitudinal bores opening from the face of said member, and stationary members adapted to support said rotative

member in said carrier member, said stationary members extending axially of said rotative member and having their outer ends slotted to conform to the slot in said rotative member and adapted to clinch the ends of the wire during the twisting operation.

6. In a device of the character described, a rotative member having a radial slot presenting diverging side walls for the reception of wires to be twisted, means for imparting rotation to said member, stationary members adapted to support said member and extending axially thereof, said members having their outer ends slotted to conform to the slot in said rotative member and adapted to clinch the ends of the wire during the twisting operation, and means to sever the free ends of said twisted wire.

7. In a device of the character described, a rotative member having a transverse radial slot presenting diverging side walls, for the reception of wires to be twisted, means for imparting rotation to said member, a carrier member having a recess for the reception of said member and further having longitudinal bores opening from the face of said member, stationary members adapted to support said rotative member in said carrier member, said stationary members extending axially of said rotative member and having their outer ends slotted to conform to the slot in said rotative member and adapted to clinch the ends of the wire during the twisting operation, and means to sever the free ends of said twisted wire.

8. In a device of the character described, a rotative member having a radial slot transversely arranged therein for the reception of wire ends to be twisted, means for imparting rotation to said member, stationary members adapted to rotatively support said member, said members extending coaxially from the opposite sides of said rotative member and each having their outer ends slotted to conform to the slot in said member there being a chamber provided intermediate the respective slots to permit the free rotation of the twisted portion of the wire and co-operating means for severing the free ends of the twisted portion.

9. In a device of the character described, a gear member adapted to be rotated, said member having a radial slot diverging from the center to the periphery thereof and having oppositely disposed central flaring terminals in the sides thereof and further being provided with an annular groove arranged concentric with said flaring terminals and stationary members having their inner ends rotatively arranged in said annular groove to support said member during rotation thereof.

10. In a device of the character described, a pair of oppositely directed tubular members removably and non-rotatively mounted

and a rotative member borne by said members, said tubular members having their outer ends slotted, there being a radial transverse slot arranged in said rotative member similarly disposed and in alinement with the slots of said tubular members, both of said tubular members being susceptible of adjustment to permit the replacement of a rotative member therebetween.

11. In a device of the character described, a rotative member having a radial slot for the reception of wires to be twisted and presenting annular grooves concentric with the axis of said member, means for imparting rotation to said member, and stationary members having their inner ends received in said grooves and adapted to rotatably support said member and having slotted portions conforming to said slot in said member and adapted to clinch the ends of the wire during the twisting operation.

12. In a device of the character described, a rotative member having a radial slot for the reception of wires to be twisted and presenting annular grooves concentric with the axis of said member, means for imparting rotation to said member, a carrier member having a recess for the reception of said member and further having longitudinal bores opening from the face of said member and stationary members having their inner ends received in said grooves and adapted to support said rotative member in said carrier member, the outer ends of said stationary members being slotted to conform to the slot in said rotative member and adapted to clinch the ends of the wire during the twisting operation.

13. In a device of the character described, a rotative member having a radial slot for the reception of wires to be twisted, means for imparting rotation to said member, and stationary members rotatably supporting said member, said members comprising tubular elements, each extending from the opposite side of said member and each having its outer end notched to conform to the said slot in said member and adapted to clinch the ends of the wire during the twisting operation.

In testimony whereof I affix my signature.

EARL D. TUBBS.
